(57) **CLAIM**

The ornamental design for the electrically powered car body, as shown and described.

DESCRIPTION

1. Electrically powered car

1.1 is a bottom plan view of an electrically powered car body showing our new design;

1.2 is a front elevation view thereof;

1.3 is a front and right side perspective view thereof;

1.4 is a rear and left side perspective view thereof;

1.5 is a rear elevation view thereof;

1.6 is a right side elevation view thereof; and,

1.7 is a top plan view thereof.

The wheels shown in broken lines are for illustrative and environmental purposes that form no part of the claimed design.
